(57) **CLAIM**

The ornamental design for an organizer stand for combination shaving and trimming device, as shown and described.

DESCRIPTION

FIG. 1 is a top, front, and left side perspective view of an organizer stand for combination shaving and trimming device showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a top, rear, and left side perspective view thereof.

The broken line disclosure is understood to represent portions of the article in which the claimed design is embodied, but which form no part of the claimed design.
